UNITED STATES PATENT OFFICE.

URBAN RUEKERT, OF WAUKESHA, WISCONSIN.

KEROSENE-OIL BURNER.

1,323,493.

Specification of Letters Patent.

Patented Dec. 2, 1919.

Application filed July 15, 1918. Serial No. 244,913.

To all whom it may concern:

Be it known that I, URBAN RUEKERT, a citizen of the United States, residing at Waukesha, county of Waukesha, and State 5 of Wisconsin, have invented new and useful Improvements in Kerosene-Oil Burners, of which the following is a specification.

My invention relates to improvements in devices for burning kerosene oil, such oil 10 being used as a substitute for coal in a furnace or stove.

My invention is explained by reference to the accompanying drawing, in which Figure 1 represents a front view thereof, and Fig. 15 2 is a detailed cross-section of the burner, taken on the line 2—2 of Fig. 1.

Like parts are referred to by the same reference numerals in both views.

1 is a kerosene oil reservoir, from which 20 oil is led to the furnace 2, through duct 3 and valve 4. Water is also simultaneously led to the furnace 2 from the reservoir 5, through the duct 6 and valve 7. The duct 6 is connected with a large air duct 8 through 25 the branch duct 9. The large duct 8 is connected with a blower 10 of ordinary construction, and the blower 10 is driven by an electric motor 11. The electric motor 11 is driven from a source of power 12, and 30 such source of power 12 may be either a dynamo or battery. 13 is a switch by which power is communicated to the electric motor through the wires 14—14. Air is driven to the furnace through said duct 8 and valve 35 15, when such air co-mingles with the kerosene and water, as such substances enter the said duct 8, the horizontal member 19* of which forms a vaporizing channel, whereby a combustible vapor is produced in the 40 burners 19—19, and said combustible vapor is ignited from the gasolene pipe 20, or in any other convenient manner. In starting the furnace, the valve 21 is first opened when

a small quantity of gasolene is introduced in the duct 20, whereby the kerosene in the 45 burners 19—19 becomes vaporized and ignited and passes up through the furnace, whereby the water in the furnace is heated.

What I claim and desire to secure by Letters Patent is:—

1. In a device of the described class, the combination with a heater, of a burner, a kerosene reservoir, a duct leading from said reservoir to said burner, an electric motor, a fan driven by said motor, an air duct leading from said fan to said burner, the horizontal member of which forms a vaporizing channel, a gasolene duct located beneath said vaporizing channel, valves for regulating the flow of air, water and kerosene to said 55 burner, a valve for regulating the flow of gasolene to said gasolene duct, a water reservoir, and a duct leading from said water reservoir to said burner.

2. In a device of the described class, the combination with a heater, of a burner, a kerosene reservoir, a duct leading from said reservoir to said burner, an electric motor, a fan driven by said motor, an air duct leading from said fan to said burner the horizontal member of which forms a vaporizing channel, means for regulating the speed of 70 said motor and fan, a gasolene duct located beneath said vaporizing channel, valves for regulating the flow of air, water and kero- 75 sene to said burner, a valve for regulating the flow of gasolene to said gasolene duct, a water reservoir and a duct leading from said water reservoir to said burner.

In testimony whereof I affix my signature 80 in the presence of two witnesses.

URBAN RUEKERT.
